SNOWDEN B. REDFIELD, OF EASTON, PENNSYLVANIA, ASSIGNOR TO INGERSOLL-RAND COMPANY, OF JERSEY CITY, NEW JERSEY, A CORPORATION OF NEW JERSEY.

AIR OR GAS COMPRESSING SYSTEM.

Application filed March 11, 1926. Serial No. 93,923.

This invention relates to return system well pumps, more especially for deep wells. Either air or gas may be used as the pressure fluid in the pumping system.

5 The objects of the invention are to enable a compressor and two tanks in the well having main well pipes and a common discharge pipe to be automatically controlled in such manner that one main pipe is alternately connected to the compressor discharge and the other to the compressor inlet and vice versa, so that the well tanks are alternately discharged and exhausted for pumping out the well. The main well 10 pipes thus form combined supply and exhaust pipes for the well tanks and when one tank is being discharged the other is being exhausted for filling purposes.

Further objects are to enable these operations to be carried out without leakage of pressure fluid to a point of lower pressure or to atmosphere in the connections and controlling devices between the compressor and the well and preferably by means of a 20 pressure actuated reversing valve and control valve controlling the reversing valve, responsive to predetermined compressor discharge pressure and to pressure on the suction side of the compressor, which may be 25 the maximum compressor discharge pressure and the minimum suction pressure selected for the operation of the system. By this means a time interval is allowed to elapse after one tank is discharged for permitting the filling of the tank before the 30 next discharge. If a full well is being pumped, this time interval will be as short as necessary for practically continuous operation.

40 The invention is shown in one of its preferred forms in the accompanying drawing, in which

Figure 1 is a diagrammatic view of the system having some of the devices in vertical section,

Figure 2 is a detail sectional view of the reversing valve with the parts in a different position,

Figure 3 is a detail sectional view of one 50 valve member of the reversing valve, and

Figure 4 is a detail sectional view of one connecting rod assembly of the control valve which controls the reversing valve.

Referring to the drawing, the well pref-

erably provided with the casing A, has two tanks or traps B and C located at any desired height therein, but in this instance shown at the bottom of the well. These tanks may, as shown for purposes of illustration, have a common discharge pipe D leading to the surface controlled by the tank valves E and F and G and H so that when one tank B is discharging to the discharge pipe D, the other tank C is filling with liquid from the well and vice versa. The tanks B and C are provided with main combined pressure fluid supply and exhaust pipes J and K respectively adapted to be connected to the discharge of the compressor L by the pipe O and to the inlet of the compressor L by the pipe P. A reversing valve mechanism or a reversing switch Q automatically controls the alternate connection of the pipes J and K to the discharge and intake of the compressor. The compressor discharge valves are indicated at R and the inlet valves at S. A control valve mechanism T responsive to predetermined compressor discharge or suction pressure, preferably maximum compressor discharge pressure or minimum suction pressure, controls the operation of the reversing valve mechanism Q.

The reversing valve mechanism includes the two cup valves U and the two cup valves V which are actuated in this instance by compressor discharge pressure, the supply and exhaust of which to and from the backs of the valves U and V is regulated by the control valve mechanism T. An air or gas induction valve W which may be any suitable type of check valve is connected by the pipe X to the point Y on the pipe P leading to the intake of the compressor for make-up purposes under certain conditions. The induction valve will be connected to a pressure fluid reservoir (not shown).

The piping of the system comprises essentially the following: a compressor suction P and a compressor discharge O, each connected between the compressor and the reversing switch mechanism Q; two pipes J and K to carry fluid pressure down the well and to exhaust it therefrom, through the reversing valve mechanism Q, and at least one pipe D to carry the oil or liquid out of the well; a pipe Z connected from the compressor discharge pipe O at the point a to

and through an auxiliary valve *b* and thence through the cylinder head *c* of the cylinder *d* of the control valve mechanism *T*; pipes *e* and *f* from the pipe *Z* to the two ball valve casings *g* and *h* respectively of the control valve mechanism *T* and pipes *j* and *k* from ball valve casings *g* and *h* to the pairs of reversing cup valves *V* and *U* respectively; and a pipe *o* from the suction line *P* of the 10 compressor to the point *p* of the control valve cylinder *d* opposite the cylinder head *c*.

The piston *q* in the control valve cylinder *d* actuates mechanism operatively connected to operate the ball valves *r*, *s*, *t* and *u* which 15 control the supply and exhaust of compressor discharge pressure to and from the backs of the reversing cup valves *V* and *U* in a manner to be described. When the 20 pressure inside the valve guide *v* of a reversing cup valve *U* or *V* is equal to the pressure surrounding the valve, the valve spring *w* holds the valve to its seat. When the pressure inside the valve guide *v* is exhausted to lower pressure or to atmosphere through one or the 25 other of the vents *x* in the ball valve casings *g* and *h*, the pressure surrounding the cup valve acting on the overhanging lip or shoulder *y* near the outer end of the valve causes the valve to actuate and open. Open- 30 ing and closing of these valves *U* and *V*, in pairs, causes the reversal of the mechanism. The pressure area of the shoulder *y* (Figure 35 2) of the valve *U* is larger than the opposed pressure area of the rim or annular base of the valve, and hence the valve will be opened and held open by pressure above atmosphere outside the valve, when the pressure inside the valve is vented to atmosphere. The 40 spring *w* is not of sufficient strength to cause the valve to close until assisted by pressure inside the valve.

With the parts of the reversing valve mechanism *Q* in the position shown in Figure 1, the valves *U* are open and the valves 45 *V* are closed so that the compressor is discharging down the well pipe *J*, and is drawing air or gas up the well pipe *K*. In Figure 2, the reversing valve mechanism is shown with the valves *U* closed and the 50 valves *V* opened after reversal and the compressor is discharging down the well pipe *K* and the well pipe *J* becomes the suction pipe. One important feature, among others, of this reversing valve *Q* resides in the fact 55 that there is no leakage which is particularly desirable in a high pressure system such as the one that forms the subject matter of the present invention. When the valves *U* and *V* are on their seats, the pressure inside and 60 outside of the valve is the same so that there is no leakage. When a valve is moved from its seat, the inside of the valve cup at the point *z*, Figure 3, forms a ground joint with the end of the guide *v* which prevents leakage. 65 These non-leakage conditions are the

same for the four valves whether open or shut, and in addition they are contained in a hermetically sealed casing.

The control valve mechanism *T* is also constructed without leaks partly because ball 70 valves *r*, *s*, *t* and *u* are used. Each pair of ball valves *r*, *s*, and *t*, *u* are moved by plungers 2 and pins 2^a actuated by connecting rods 3 connected to cranks, eccentrics or cams 4 on the shaft 5, which shaft is actuated by the rack 6 on the piston rod 7 of the piston *q* cooperating with the pinion 8 loose upon the shaft 5. A ratchet and pawl mechanism 9 and 10 between the pinion 8 and the shaft 5 transmits power to the shaft in one 80 direction. The cranks 4 are set oppositely as indicated in the drawing and in Figure 1 the ball valves *r* and *u* are removed from their seats while the ball valves *s* and *t* are pressed to their seats. In this position of 85 the valves pressure fluid is supplied to the reversing cup valves *V* for holding them closed while the backs of the cup valves *U* are exhausted of pressure. One half revolution of the shaft 5 causes the reversal of the 90 positions of the ball valves which causes reversal of the positions of the cup valves *U* and *V* as indicated in Figure 2 thus reversing the flow of pressure fluid between the compressor and the well.

In the operation of the system, the discharge pressure of the compressor will continue to rise until the liquid level falls in the bottom of one well tank or the other, substantially to the bottom of the tank. The 100 auxiliary valve *b* operating in connection with the control cylinder *c* is set so that at the maximum pressure, pressure fluid will be supplied through the pipe *Z* to the cylinder *d* thus actuating the piston *q* forwardly and 105 rotating the shaft 5 through one half revolution so that the reversing valve mechanism is operated as described. The pressure throughout the system will then be equalized which will cause the auxiliary valve *b* to 110 open the cylinder *d* to lower pressure or to atmosphere. The opposite end of the cylinder *d* is subject to pressure from the suction side of the compressor from the pipe *o*, which is at some equalized intermittent pressure below the maximum and this pressure will cause the control piston *q* to move rearwardly, but the ratchet and pawl mechanism 9 and 10 is so arranged that the shaft 5 is not rotated and the reversing valve mechanism 115 will be unaffected. The pressure on the discharge side of the compressor will begin to build up and the pressure on the suction side will fall. When the discharge pressure has again reached its maximum for which the auxiliary valve *b* is set, said valve will again admit pressure fluid to the cylinder *d* causing reversal of the positions of the ball valves for the next operation of the reversing valve mechanism *Q*. At this particular 120

time in the cycle it is to be understood that the pressure in the opposite end of the cylinder *d* is at a minimum approximating atmospheric pressure so that there is no resistance to the forward movement of the piston *q* except the tension of the spring 11. This spring 11 is to prevent the piston *q* from being moved forwardly as the suction side of the entire system falls below atmosphere or to about the low pressure in the exhaust side. The spring 11 is sufficiently strong to resist the tendency to suck the piston *q* forward, but not strong enough to hold back the movement of the piston *q* when subjected to maximum discharge pressure behind the piston.

In order that the lower ball valves *s* and *u* of each pair may come to their seats when actuated by the connecting rods and to make allowance for mechanical inaccuracy, each connecting rod is provided with a compression element as shown in detail in Figure 4 in the form of a sliding joint 12 and spring 13 between the connecting rod members 15 and 16. Pins 17 loosely connect the members 15 and 16 and permit a lost motion connection as indicated in Figure 4. By means of this construction the ball valves *s* and *u* become seated before the cranks reach dead center and when fully seated, the springs 13 are compressed.

The auxiliary valve *b* may be of any suitable type, but is preferably like that disclosed in U. S. Patent No. 1,138,278, granted May 4, 1915, to J. H. Castle and W. G. Rogers which is so constructed that the valve operates to admit a certain predetermined pressure to a regulating mechanism such as the control valve cylinder, until the pressure falls to a certain amount below that required to operate the regulating mechanism, in which case the valve returns to its original position, allowing the regulating mechanism to exhaust to some lower pressure, such as atmospheric pressure. I have merely indicated the valve chest *b*, the adjustable plug 14 and the spring cup 28, corresponding to similar parts similarly numbered in said patent. As stated, the auxiliary valve *b* is set to operate with the maximum compressor discharge pressure at which point it will open connection to the control valve cylinder *d*, while at other times said control valve cylinder is vented to lower pressure or to atmosphere.

In the operation of the system with the parts in the position indicated in Figure 1, the compressor is discharging into the well tank *B* for evacuating said tank through the surface discharge pipe *D* and the intake of the compressor is connected to the well pipe *K* so that air or gas is being drawn from the well tank *C* which is in the act of filling. This condition will continue until maximum compressor discharge pressure is

reached at which point the auxiliary valve *b* will be actuated to supply pressure to the control valve cylinder *d* and the forward movement of the piston *q* will reverse the positions of the ball valves which in turn will cause reversal of positions of the two pairs of reversing valves *U* and *V*. These reversing valves will assume the position indicated in Figure 2 and the compressor will discharge down the well pipe *K* to the tank *C* and will suck air or gas from the well tank *B* through the well pipe *J*, which is then connected to the compressor intake. This cycle of operations of ultimate filling and discharging of the well tanks *B* and *C* will continue.

I claim:

1. In a pressure fluid compressing system, the combination of a compressor and main combined pressure fluid supply and suction pipes leading from the compressor, a pressure fluid actuated automatic reversing valve mechanism interposed in said main supply and suction pipes, comprising a casing, valves in said casing having their backs adapted to be subjected alternately to discharge pressure or lower pressure, a control valve mechanism interposed between the compressor and the reversing mechanism and consisting of a cylinder and piston therein subject to maximum and minimum pressure on one side and to compressor suction pressure on the other side, valve casings and double valves controlling the connections to the reversing mechanism, and mechanical means operated by the said control valve piston for actuating said double valves, whereby one main pipe of the system is automatically and alternately connected to the compressor discharge and the other to the compressor inlet and vice versa.

2. In a pressure fluid compressing system, the combination of a compressor and main combined pressure fluid supply and suction pipes leading from the compressor, a pressure fluid actuated automatic reversing valve mechanism interposed in said main supply and suction pipes, comprising a casing, four valves in said casing adapted to be actuated in pairs for alternately connecting one main pipe to the compressor discharge and the other to the compressor inlet and vice versa, said reversing valves being controlled by alternations of discharge pressure and lower pressure exerted on their backs, and a control valve mechanism controlling the pressure exerted on the backs of said reversing valves, and consisting of a main fluid actuated piston and valves actuated thereby interposed in the pressure fluid connections leading to the backs of the reversing valves.

In testimony whereof I have signed this specification.

SNOWDEN B. REDFIELD
